UNITED STATES PATENT OFFICE.

JAMES W. THOMPSON, OF BEAVER, OKLAHOMA.

WASHING MACHINE.

Application filed October 26, 1923. Serial No. 670,949.

To all whom it may concern:

Be it known that JAMES W. THOMPSON, a citizen of the United States, residing at Beaver, in the county of Beaver and State of Oklahoma, has invented certain new and useful Improvements in Washing Machines, of which the following is a specification.

This invention relates to a clothes washing machine in which the clothes are subjected to a compressing or squeezing action while in a tub or container whereby dirt and all foreign matter may be conveniently and thoroughly removed therefrom.

A further object of the invention is to provide a clothes washing machine which may be operated either by hand or by power and which is so designed and constructed as to provide for a quick and thorough cleaning of the clothes without subjecting the same to injury.

With the above and other objects in view this invention resides generally in the particular details of construction, design and combination of parts as hereinafter set forth and described, reference being had to the accompanying drawings, wherein:

Figure 1 is a plan view of the washing machine.

Figure 2 is a vertical section, and
30 Figure 3 is a side elevation with the plunger and handle in outermost position.

Describing the invention in detail, 10 designates the container for holding the clothes to be washed and 11 designates a drain opening at the bottom of the container for draining the tub whenever required. This opening may be closed by any suitable plug means capable of being removed.

On one side of the tub and adjacent the 40 upper edge thereof is fastened a plate 12 carrying upwardly projecting bearing brackets 13 which serve to provide a hinged support for the handle structure.

The handle comprises a rectangular frame 45 which may be constructed of side and end pipe sections 14 and 15 coupled at their respective meeting ends by elbow couplings 16 and T-couplings as illustrated; the elbow couplings being at the inner ends of the frame and presenting stop shoulders having abutment with brackets 13 to limit movement of the frame laterally of the brackets. The frame is thus mounted to swing upwardly and over the upper open end of tub 50 10 so as to lie horizontally across the tub and

when so positioned may be alternately raised and lowered either by hand, or by power suitably applied. In the operation of the machine, the clothes are compressed or squeezed between a pair of plates 18 and 19, the former of which normally rests upon the bottom of the tub and supports the clothes, while the latter is carried by the handle frame. The frame is provided on opposite sides with T-couplings 20 between which a cross member 21 is supported; these couplings 20 being so located on the handle frame as to be centered, or nearly so, with respect to the tub when the frame is disposed across the latter as above explained. Cross 70 bar 21 supports a pair of T-couplings 23 and 24 mounted to revolve on the cross member and being respectively provided with a depending arm as indicated at 25 and 26 respectively. Each arm is threaded at its opposite ends, one of which is threadedly engaged with a T-coupling while the other is inserted thru a suitable opening in plate 19, lock nuts 27 and 28 being employed to detachably secure the plates to each arm. 75

Plates 18 and 19 are constructed of wire mesh and plate 19 is adapted to have a snug fit with tub 10 so as to be conveniently reciprocated therein upon manipulating the handle so as to have an up and down movement after the manner of a plunger. Consequently, when the handle structure is moved downwardly, plate 19 will be forced in the direction of plate 18 and the clothes between the plates will be alternately compressed and released during the operation of the machine, the compression of the clothes serving to remove dirt and foreign matter therefrom, it being understood that the tub 10 is suitably filled with hot soapy water in 95 which the clothes are submerged.

From the foregoing it is thought that the objects and advantages of the invention can be readily understood and that further detail description of the operation thereof is 100 unnecessary.

What is claimed is:

A washing machine comprising a single container for the clothes and washing liquid, 105 a removable reticulated plate disposed in the container and held in spaced relation to the bottom wall thereof, a reticulated plunger plate movable toward and away from the first mentioned reticulated plate, a handle structure including a pair of spaced parallel 110

operating bars, and a connecting bar, means hingedly connecting the connecting bar to the upper edge of the container at one side thereof, a transversely extending cross bar connected to the operating bars, sleeves rockably mounted on the cross bar, plunger rods carried by the sleeves and connected to

the plunger plate, the terminals of the operating bars opposite to the connecting bar being extended beyond the container, and a handle grip secured to the terminals of the operating bars.

In testimony whereof I affix my signature.

J. W. THOMSON.
